LUCIEN R. GUILBAUD, OF NEW YORK, N. Y., ASSIGNOR TO WESTERN ELECTRIC COMPANY, INCORPORATED, OF NEW YORK, N. Y., A CORPORATION OF NEW YORK.

INDUCTANCE DEVICE.

Application filed June 20, 1924. Serial No. 721,369.

This invention relates to inductance devices of the type known in the art as retard coils, transformers and the like, and particularly to shell-type magnetic cores for such devices.

An object of the invention is to improve the efficiency of magnetic cores of the general type referred to.

More specifically the invention has for its object to produce a shell-type core having such a shape and such dimensions as to give the maximum inductance for a given overall area of lamination.

In the design of transformers for many purposes, such as telephony and the like, the essential points to be considered are: the inductance of the coil, its D. C. resistance, its magnetic leakage and the distributed capacity of the winding. It is generally necessary to consider all of the above factors in the design of transformers to meet the particular circuit requirements as to load, impedance, etc., while in the case of retard coils, the problem of obtaining the maximum ratio of reactance to D. C. resistance is most essential. In input transformers for vacuum tubes, however, it is well known that the D. C. resistance of the secondary winding is unimportant and that in all cases the smallest size of wire available can be used, the tube impedance being so high that the D. C. resistance of the secondary winding is negligible. While in special cases, as in the case of input transformers, the D. C. resistance need not be considered, as a general proposition, one of the main considerations in transformer design is the problem of obtaining a given inductance with the smallest possible D. C. resistance. Hence in designing a new type of transformer, it is often, if not generally advisable to design it so that it will give a sufficient inductance to be useful as an input transformer, and, at the same time, have the D. C. resistance within reasonable limits so that efficient transformers for other uses and retard coils may be wound on the same design of core.

In accordance with the invention, it has been found that the most advantageous proportions of a shell-type core for securing a maximum inductance for a given over-

all area of lamination are obtained when the window apertures or winding spaces are square having a dimension of $0.8X$ on a side, the distance between the window apertures is $0.150X$, and the distance between the window apertures and the adjacent outer sides of the lamination is $0.125X$, where X is one-half the length of the longest side of the lamination.

The principal features and objects of the invention will be clear from the following detailed description read in connection with the accompanying drawings.

In the drawings, Fig. 1 shows a transformer having a core of the general type of the invention, Fig. 2 shows the dimensional notation used in the specification, Fig. 3 shows the most advantageous dimensions of a core as embodied in the invention, Fig. 4 is a curve showing the relation between the constant K of Fig. 2 and the inductance, and Fig. 5 shows a section along the line 5-5 of Fig. 2. Like parts bear like reference characters throughout the several drawings.

Referring to Fig. 1 a transformer is shown comprising a laminated, shell-type core 1 having outer branches 2 and central branch 3, primary winding 4 and secondary winding 5. Fig. 2 shows a plan view of a lamination of the core 1 indicating the dimensional notation which will be used in the description. The dimensions are all referred to the half length X of the lamination, the window 6 having a dimension KX lengthwise of the lamination, the remainder $(1-K)X$ being distributed between the solid branches 2 and 3, a part a $(1-K)X$ in the center branch and the remainder $(1-a)(1-K)X$ in one of the outer branches.

If we consider the core 1 as a lamination having a thickness of unity, the magnetic permeability being μ for a given number of turns N in the winding the inductance will be

$$L = 4\pi N^2 \mu 10^{-9} \frac{A_1 A_2}{l_1 A_2 + l_2 A_1} \quad (1)$$

where A_1 is the area of a vertical section through the central branch 3 of the core

- along the line 5-5, as shown in Fig. 5; A_2 is twice the area of a vertical section through either outer branch 2 of the core along the line 5-5, as shown in Fig. 5; the two outer branches 2 of the core being considered as one branch of double area; l_1 the mean length of the portion of the magnetic circuit within the center branch 3, and l_2 the mean length of the portion of the magnetic circuit within one of the outer branches 2. It is assumed that the area A_1 of the cross section of the central branch 3 of the core is uniform between the lines 7-9 and 8-10, and that the outer branch 2 of the core is also of uniform cross section.
- As a first step in determining the most efficient dimensions of the core for a given inductance, the area of the window 6 is assumed to be a constant and the relationship between the two cross sections A_1 and A_2 is determined. The best shape of window will be that which for a given number of turns in the winding will offer the shortest length of magnetic path. Now for all coils wound on a spool it is necessary to use a rectangular window. It is well known that

$$L = \frac{4\pi N^2 \mu 10^{-9} \cdot 2a(1-K) \cdot 2(1-a)(1-K)}{2(1-a+aK)(1-a)(1-K) + (2+K) \cdot 2a(1-K)} \quad (4)$$

Holding N constant, the location of the window, will be determined. To determine the maximum of L when a varies, the variable part of equation (4) will be studied. This is

$$\frac{a(1-a)}{(1-a+aK)(1-a)+(2+K)a}$$

The derivative of this expression with respect to a is

$$\frac{d}{da}(3) = \frac{[a^2(1-K)+2aK+1](1-2a)-a(1-a)[2a(1-K)+2K]}{[a^2(1-K)+2aK+1]^2} = \frac{-a^2(K+1)-2a+1}{[a^2(1-K)+2aK+1]^2} \quad (6)$$

- 65 Making the numerator $-a^2(K+1)-2a+1=0$, and solving, two roots are obtained for values of a between which the derivative of equation (3) with respect to a will be positive, namely

$$70 \quad a = \frac{1 + \sqrt{2+K}}{-(K+1)}$$

and

$$75 \quad a = \frac{1 - \sqrt{2+K}}{-(K+1)} \quad (7)$$

The higher value,

$$a = \frac{-1 + \sqrt{2+K}}{K+1} \quad (8)$$

$$L = 4\pi K^4 X^4 \mu 10^{-9} \frac{2a(1-K)X \cdot 2(1-a)(1-K)X}{2l_1[(1-a)(1-K)X + 3a(1-K)X]} \quad (9)$$

- 95 X will be assumed to be constant. Then, L will be a maximum when $K^4(1-K)$ is maximum, that is, when

$$4K^3 - 5K^4 = 0 \quad (10)$$

$$K=0.8 \quad (11)$$

of all rectangular figures the square offers the largest area for a given perimeter. The factor

$$\frac{A_1 A_2}{l_1 A_2 + l_2 A_1}$$

20

of equation (1) reduces to $\frac{A}{l}$ if $l_1 = l_2 = l$,

which means that if the two cross-sections A_1 and A_2 are equal for the central and outer branches, the ideal window would be square. If l_1 differs from l_2 , this is no longer strictly true. However, a square window will be assumed as an approximation. The result obtained will show that l_1 is very little different from l_2 and that the approximation is justified. Then, referring to Fig. 2, as the thickness of the core is unity, it is apparent that

$$A_1 = 2a(1-K)X \quad (2)$$

and

$$A_2 = 2(1-a)(1-K)X \quad (3)$$

Substituting equations (2) and (3) in equation (1), X disappears and equation (1) reduces to

$$\frac{a(1-a)}{a^2(1-K) + 2aK + 1} \quad (5)$$

reducing to

60

therefore, will correspond to a maximum for L , and also it is the only value which can be used as the other root is negative. From equation (8), then, a can be determined, provided K is known.

The next step will be to determine the best dimensions for the window. This can be done by replacing N^2 in equation (4) by $K^4 X^4$ which is proportional to it. Also, as window 6 of Fig. 2 is square, the mean magnetic circuit along ACDE will be approximately a square and l_2 may be replaced by $3l_1$. Then, equation (4) will take the form

85

90

95

Solving equation (10), an approximate value for K is obtained.

Substituting this value of K in equation (8), a corresponding value for a is obtained.

$$a=0.374 \quad (12)$$

The values of K and a having been determined, the complete shape of the lamination is known. Substituting the values of K and a in the dimensional units shown in Fig. 2, we will obtain the dimensions as functions of X . The actual proportions are shown in Fig. 3, the windows 6 each being $0.8X$ square, the central solid branch $0.150X$ wide and all other solid branches being each $0.125X$ wide.

To verify the results obtained, values of K^4X^4 .

$$20 \quad \frac{A_1 A_2}{l_1 A_2 + l_2 A_1},$$

proportional to the inductance, were calculated for various values of K and plotted giving the curve shown in Fig. 4. This shows the existence of a maximum for $K=0.8$. The calculations show that the approximations made in determining K did not impair the accuracy of the results very much, as a variation of approximately only one per cent shows in the numerical results. Also, taking any two values for K , for instance $K=0.8$ and $K=0.4$, and calculating a , values of $a=0.373$ and $a=0.391$, respectively, are obtained. If the values of K^4X^4

$$\frac{A_1 A_2}{l_1 A_2 + l_2 A_1}$$

40 corresponding to these values of a and K are calculated, the results show that they correspond to a maximum for the inductance L , showing that the approximations made were justified.

Throughout our calculations, we have assumed a thickness of unity for the core. Calculation to determine the best thickness for the core, that is, the thickness giving the largest inductance for a given volume of magnetic material used, shows that the inductance will steadily increase with a decreasing thickness of the core the overall volume of the core being kept constant. Finally, we would have a lamination infinitely thin and of infinitely large area and a coil with an infinite number of turns. This not being practicable, the question of thickness will have to be determined by other considerations such as minimum D. C. resistance or minimum weight. Our two determinations, that is, (1) location of window, and (2) size of the window are independent of each other. If both values are applied strictly, we will obtain a shape of

lamination as shown in Fig. 3, and the inductance of the coil would then be given by

$$L = .724\mu t 10^{-9} \left(\frac{X}{\omega} \right)^4$$

70

where μ is the permeability of the core, t the thickness of the core in centimeters, and ω the effective cross section of the wire used expressed in the same units as X , so that L being given we can determine t , or L and t being given, we can determine ω .

If a transformer is to be designed that will give a certain inductance with the smallest possible volume, the first step will be to determine from considerations of the amount of current to be carried the smallest size of wire that can be used, which will give ω . Then, a probable value for t can be assumed and X obtained from

$$85 \quad X = \omega^4 \sqrt{\frac{L 10^9}{0.724\mu t}}$$

which is simply equation (4) in which a and K have been replaced by their numerical values. It is obvious that by varying the dimension t , the other dimensions can be changed correspondingly to obtain the proportions that may be desired for appearance, convenience of mounting, etc.

The value of K , which determines the size of the window, may be varied from the value of 0.8 given, as may be desired, particularly where the relative cost of a particular core material and the wire material in the windings is an important consideration. It will be noted that, as K is increased, the volume of the winding will be increased and that of the core decreased. By a simple calculation, making use of the equations given above, the value of K which will just about balance the costs of the core and winding can be determined. This value of K will not be very different from the optimum value of 0.8 as derived above.

It has been determined by calculation based on coils now in use and heretofore considered as standard that by adopting the proportions in accordance with this invention, very valuable results can be obtained. In certain of these coils, it was calculated that for a given overall area of lamination, changing the location of the window without changing the number of turns would give a gain in inductance as high as 12 per cent while changing the size of the window as well as its location but keeping the overall area of lamination constant, owing to an increase in the number of turns that can be used, would give a gain in inductance as high as 110 per cent.

Although, for convenience of illustration and description, a laminated core of the shell-type has been shown in the drawings and referred to in the description, the inven-

- 4
- tion is applicable to any other core of the shell-type. The shell-type core referred to in the description and claims is the well-known core having at least two winding spaces or apertures surrounded by a shell comprising a central branch and two outer branches. While for convenience in description laminations have been referred to, it is obvious that, as pointed out above, no actual laminations need be used but a solid or other type of core structure can be used, in which case the laminations may be considered as being present and separated by imaginary planes.
- 15 15. What is claimed is:
1. A shell-type core for an inductance device, having a central branch and two outer branches in shunt to each other and in series with said central branch, said central branch being of greater cross-section than either outer branch but of less cross-section than both outer branches together.
  2. A shell-type core of uniform thickness as claimed in claim 1 in which the window apertures are of square cross-section, said square cross-section of said window apertures having sides substantially four-tenths ($\frac{4}{10}$) of the length of the longest side of the lamination of the core in length.
  3. A shell-type core of uniform thickness as claimed in claim 1 in which the central limb between the window apertures has a width substantially 0.075 times the length of the longest side of the lamination of the core.
4. A shell-type core of uniform thickness 25 as claimed in claim 1 in which each of the outer limbs has a width substantially one-sixteenth ($\frac{1}{16}$) of the length of the longest side of the lamination of the core.
5. A shell-type core of uniform thickness 40 as claimed in claim 1, in which the window apertures are square having sides each four-tenths ($\frac{4}{10}$) the length of the longest side of the lamination of said core in length, the central limb between said window apertures having a width substantially 0.075 times the length of the longest side of the lamination of said core, and each of the outer limbs of said core having a width substantially one-sixteenth ($\frac{1}{16}$) the length of the 50 longest side of the lamination of said core in length.
6. A shell-type core for an inductance device, comprising a central branch and two outer branches, said central branch having 55 a cross-section substantially six-tenths ($\frac{6}{10}$) the cross-section of both outer branches together.
7. A shell-type core for an inductance device, comprising a central branch and two outer branches, said outer branches being of equal section and each substantially eight-tenths ($\frac{8}{10}$) the cross-section of said central branch.

In witness whereof, I hereunto subscribe 65 my name this 12th day of June A. D., 1924.

LUCIEN R. GUILBAUD.
